UNITED STATES PATENT OFFICE.

CHARLES A. JOUETT, OF PRYSE, KENTUCKY.

CONTINUOUS PETROLEUM-REFINING APPARATUS.

1,415,876.

Specification of Letters Patent. Patented May 16, 1922.

Application filed September 23, 1918. Serial No. 255,331.

To all whom it may concern:

Be it known that I, CHARLES A. JOUETT, a citizen of the United States, and resident of Pryse, in the county of Estill and State of Kentucky, have invented certain new and useful Improvements in a Continuous Petroleum-Refining Apparatus, of which the following is a specification.

The present invention relates to the refining of oils such as petroleum, and relates more particularly to an improved process and apparatus for producing this result.

It is found by actual practice that the present processes and apparatus for refining petroleum are very wasteful and extravagant not only in the consumption of fuel, but also in the capacity of the apparatus employed. The practical stills employed are arranged lengthwise in a horizontal position and are connected from one to the other so that they may be operated in a continuous manner. This is known in practice as a continuous still, and the tanks or containers must be filled to half of their capacity to obtain maximum efficiency of the apparatus. There is thus only fifty per cent of the internal space remaining for the accumulation of the vapors, and it is essential to maintain a very hot fire against the under sides of the tanks for thoroughly heating the relatively large solid masses of fuel in the lower halves of the tanks.

It is therefore the object of the present invention to provide a continuous still which is so arranged that a small volume of heat may be utilized in the heating of the various compartments or chambers of the stills and wherein a relatively small proportion of oil is brought into intimate contact in a relatively thin surface coating of the oil with a heating medium to insure the evaporation of the oil in a relatively short time; to utilize the heat which heretofore has been allowed to escape; to provide separate compartments for the volatilization of the recovered oil and for independently regulating the heating of the compartments; and to provide means for recovering the oil condensing before final separation.

The present invention also provides for treating the vapor to grade and distribute the oil, and to maintain the various desired temperatures of the oil for producing the

vapor of the desired specific gravity for the production of the particular grades of the oil desired.

Various other objects and advantages of this invention will be in part described in, and in part understood from, the following detailed description of one form of apparatus embodying the features of this invention and by which the improved process may be practiced, the structure being illustrated in the accompanying drawings, wherein—

Fig. 1 is a vertical section through a still and refining apparatus constructed according to the present invention.

Fig. 2 is an enlarged vertical section through the upper portion of the still.

Fig. 3 is a horizontal section through the same taken on the line 3—3 of Fig. 2.

Fig. 4 is a fragmentary, vertical sectional view through the vapor treating and rock towers, illustrating the connection therebetween and the condensate returns from the rock towers.

Fig. 5 is a horizontal section through the same taken on the line 5—5 of Fig. 4.

Fig. 6 is a detail fragmentary view showing the damper control for one of the still chambers.

In setting forth the process of this invention the same will be described in detail with reference to the structure illustrated in the accompanying drawings, and referring thereto 10 designates a furnace of any approved type provided in its bottom with a fuel bed 11 and at its top with a coil chamber 12. Leading from the back of the furnace 10 is a relatively large vertical stack 13 in the form of a preferably cylindrical tower provided with inwardly extending partition flanges 14 in suitably spaced-apart relation which divide the tower 13 into a plurality of superposed compartments. A flue 15 leads directly from the furnace 10 and rises at one side throughout the height of the stack 13, the flue 15 being closed at its upper end by a top wall 16, and communication being established between the flue 15 and the superposed compartment of the stack by flue openings 17 independently controlled by dampers 18. The dampers 18 may be of any desired construction, and in the present instance are disclosed as of the shutter type and pivotally mounted upon a

shaft 19 provided with an outwardly extending handle 20 by means of which the damper may be regulated by the turning of the shaft.

The compartments of the stack 13 inter-
5 communicate at the far side of the stack, or at that side remote from the flue 15, inter-
communication being established by the pro-
vision of relatively small passages or open-
ings 21 in the partition flanges 14, as shown
10 in detail in Fig. 3, and the stack 13 prefer-
ably opening above the superposed openings
21 to admit the direct escape of the products
of combustion or gases without requiring
15 the circulation thereof consecutively through
the various compartments. In this manner
the temperature of the various compart-
ments may be independently controlled by
the regulation of the damper 18.

The main portion of the apparatus which
20 may be herein termed as the still is arranged
within and supported upon the stack 13, and
comprises a plurality of superposed cham-
bers or tanks 22, a tank 22 being arranged
25 in each compartment of the stack and adapt-
ed to fit snugly against the inwardly ex-
tending partition flange 14 thereof to pro-
vide a substantially sealed annular chamber
in the stack about each of the still chambers.
The heating medium thus entirely surrounds
30 the still chambers and a relatively large
heated surface area is thus provided.

An oil receiving and heating coil 23 is
suitably arranged in the coil receiving cham-
ber 12 of the furnace and preferably has
35 an inlet 24 at the upper end of the coil and
an outlet pipe 25 leading from the lower
end of the coil and extending to the top of
the still. The upper compartment 22 of the
still has therein a distributing rose or mem-
40 ber 26 which is in communication with the
pipe 25 to receive oil therefrom, the dis-
tributing member 26 having downwardly
directed openings for spraying the heated
oil or vapor downwardly through the upper
45 compartment 22. The upper compartment 22
is provided with a radially inclined bot-
tom 27 and is provided, at the marginal edge
of the bottom with a substantially annular
slot or opening 28 through which oil flowing
50 over the bottom 27 may escape into the sub-
imposed compartments. Supported upon
the bottom 27 is a preheating coil 29 adapt-
ed to raise the temperature of oil falling
55 upon the bottom 27 and assist in vaporizing
the same. From the marginal edge of the
bottom 27 there depends an annular row of
pipes 30 spaced concentrically inward from
the plane of the outer wall of the compart-
60 ment 22 and adapted to project down into
an annular space formed between the inner
and outer walls 31 and 32 of the subimposed
compartments. The pipes 30 terminate
65 short of the bottom of the said space of the
subjacent compartments and form therein
traps for holding and collecting the drip-

ping oil from the bottom 27 of the upper com-
partment against the outer wall 32 of the
lower compartment. The outer wall 32 of
the lower compartment provides a heating
70 surface, over which the relatively thin film
of oil passes, the oil being vaporized and di-
rected by the trap pipes 30 into the space
between the same and the inner wall 31, and
into the lower compartment. The vapors
75 which thus enter the top of the lower or
second compartment are trapped therein,
and any condensate resulting therefrom
falls upon the bottom 27 of the second com-
partment, from which the oil passes into the
80 third compartment as above set forth. The
action is similar throughout the various
superposed compartments employed in the
still.

As shown in Fig. 2, the damper 18 from
the flue 15 to the heating chamber surround-
85 ing the second compartment 22 is closed.
When this is opened, the products of com-
bustion pass from the flue 15 into the annular
passage and raise the temperature of the
90 second still compartment to the desired de-
gree for vaporizing the oil at the required
temperature.

Opening into the top of the chamber 22
is a vapor receiving pipe 33 adapted to con-
duct the vapors accumulating in the upper
95 end of the compartment 22 to corresponding
compartments in a vapor treating tower ar-
ranged preferably adjacent to the stack 13.
The vapor treating tower comprises a plu-
rality of superposed sections 34 correspond-
100 ing in number and height, preferably, to the
number and height of the compartments of
the still. Each compartment 34 is provided
with spaced-apart perforated diffusing discs
35 downwardly over and through which the
105 vapor is adapted to pass, and which supports
a preferably centrally arranged heat dis-
tributing pipe 36 provided with radial open-
ings thereabout for delivering jets of steam
110 to the downwardly moving vapor above, be-
tween and below the diffusing discs 35 for
thoroughly impregnating the vapor and in-
creasing the heat to the desired saturation
115 point. The treated vapor passes from the
lower end of each compartment 34 through
a pipe 37 into the lower end of a correspond-
ing compartment 38 of the rock tower. The
120 pipe 37 opens into the lower end of the
compartment 38 in slightly spaced relation
to the bottom thereof to admit the accumu-
lation of condensate at the lower end of the
compartment or chamber 38. The return
125 pipe 39 leads from the bottom of the com-
partment 38 to the correspondingly subja-
cent chamber 22 of the still tower for return-
ing the condensate to the tower to be re-
vaporized and subsequently treated as above
set forth. The return pipe 39 is preferably
provided with a trap 40 therein for sealing
130 the pipe 39 against the passage of vapor

from the subjacent chamber 22 directly into the rock tower.

Each compartment 38 of the rock tower is provided with a plurality of superposed perforated discs 41 adapted to support suitable filtering substances, such as rock ground to the desired fineness. As illustrated in Fig. 4, the masses of rock 42 are supported upon foraminous discs, and the vapors, subsequent to their preheating, pass upwardly through the various filtering masses, for extracting foreign substances from the vapor and thoroughly admixing the vapor with the steam, the vapor products being carried from the upper end of the compartment 38 through a delivery pipe 43, which may be connected to a suitable condenser of any well-known type. The steam pipes 29 and 36 may be connected to any suitable source of steam, such as to a common supply pipe 44, and any corresponding number of compartments or chambers may be employed in the still, and the towers connected thereto for producing the desired number of grades of oil, the lower compartment yielding a heavier grade of oil, and the product from which may be converted into lubricating and cylinder oils by the treatment of the residue in the ordinary lubricating still.

In carrying out the process of this invention it will be noted that the oil is continuously fed through the still and that the latter requires but practically eight per cent of its interior space for the reception of oil being treated, and that practically ninety-two per cent of the space within the still provides for the storage or accumulation of vapor. It will also be noted that the entire surface of the still is subject to direct contact with the heating medium, and that the vapor or oil is fed to the enclosing heating surface in a relatively thin film or sheet, insuring instantaneous and thorough heating of the vapor or oil.

It will also be noted that the process embodies the trapping of the condensate and

returning it for a subsequent treatment as a heavier grade of oil.

What is claimed:

1. In an apparatus for refining oil, the combination of a plurality of superposed chambers, provided with annular traps at their lower ends, the trap of each chamber opening into the top of the subjacent chamber, means for feeding oil into the top of the uppermost chamber, the oil being adapted to drain from the upper chamber through the trap into the tops of the subjacent chambers, heating means surrounding said trap, means for independently carrying off the vapors from the chambers of the still, and means for independently treating the vapors.

2. In oil refining apparatus, the combination of a still, including a plurality of superposed chambers, each chamber provided with a radially inclined bottom and having a substantially annular passage at the marginal edge of the bottom, each chamber also having a depending trap leading from the annular passage, and adapted to open into the top of the subjacent chamber, means for heating the bottoms of the chambers, means for heating said traps, and means for independently carrying off the vapors produced in the separate chambers.

3. In apparatus for refining oil, the combination of a still, including a plurality of superposed connected chambers, means for feeding heated oil to the uppermost chambers, the said chamber provided with spaced annular walls and the superadjacent chambers provided with depending trap walls adapted to fit between the annular walls of the subjacent chamber to form annular traps connecting the chambers and surrounding the same, circular heating chambers surrounding the chambers of the still, means for directing a heating medium independently to the heating chambers, and means for independently collecting the vapors from the chambers of the still.

CHARLES A. JOUETT.
